UNITED STATES PATENT OFFICE.

CHARLES J. HEJDA, OF CHICAGO, ILLINOIS, ASSIGNOR TO ASSOCIATED ENGINEERS COMPANY, OF CHICAGO, ILLINOIS.

CONTACT-MAKING VOLTMETER.

1,101,798.

Specification of Letters Patent. Patented June 30, 1914.

Application filed October 11, 1910. Serial No. 586,468.

To all whom it may concern:

Be it known that I, CHARLES J. HEJDA, a citizen of the United States, residing at Chicago, in the county of Cook and State of Illinois, have invented a certain new and useful Improvement in Contact-Making Voltmeters, of which the following is a full, clear, concise, and exact description, reference being had to the accompanying drawings, forming a part of this specification.

My invention relates to regulating devices and while not so limited is of particular utility in connection with what are styled contact making volt meters. These so called contact making volt meters comprise means operable with changes in pressure to increase or decrease the voltage of supply circuits. I will style the instrument of this character in connection with which I am describing my invention a contact making volt meter throughout this specification in conformity with present day terminology. These contact making volt meters control a movable contact or contacts and the movement of these contacts is in conformity with changes in voltage of a supply circuit whose pressure it is desired to maintain as nearly constant as is possible. It is found in practice that when the voltage is at or near normal, these contacts oscillate rapidly or vibrate close to the fixed contact terminals with which they are to be connected in operative relation periodically, and thus burn these contacts and render these instruments very delicate, requiring most frequent attention, and by reason of this delicacy and burning of the contacts, weld the contacts together in such a way that the instrument is frequently inoperative for the purpose intended.

My invention is designed to obviate this difficulty, but I wish it understood of course that my invention is not limited in its application to contact making volt meters, but is capable of a great variety of uses. To properly describe my invention, however, in connection with its application to a given system wherein its corrective influence is of great utility, I show it in this application as applied to a system of so called contact making volt meters and will describe it in this connection. Generally speaking my invention provides means to overcome the vibrations of these contact points under consideration and to hold them in either positive

fixed contact or else to insure their separation a sufficient distance to prevent the objectionable effects of vibratory contact and arcing of the current above outlined.

In the form shown herein my invention takes the form of two solenoids controlling a common core, which core is in association with a movable contact. The two solenoids depend preferably for their current upon such current as is supplied when the contact points are close together or in vibratory relation. My invention as set forth in this particular embodiment as outlined above and the particular form which it takes under these conditions will now be described in detail by reference to the accompanying drawings, in which:

Figure 1 is a front view of the apparatus of my invention shown in connection with a contact making volt meter; Fig. 2 is a side view thereof, and: Fig. 3 is a diagrammatic circuit arrangement illustrative of the connections of the various devices.

The contact making volt meter consists of a winding 1 having two coils, a series coil and a shunt coil as will appear later, which are mounted upon a suitable bracket 2 and having a movable core 3 associated with an adjustably mounted guide 4. A coil of soft wire such as solder 5 is used to provide more or less weight for the core as may be necessary. Terminals 6 permit entrance of the current through the series coil of the winding 1. The core 3 is attached to a stem 7, which stem is pivotally secured to a rocking lever 8, which rocking lever is pivoted at 9. A contact post 10 and a spiral connecting wire 11 furnish electrical connection to the rocking lever and the bracket 12 supports the rocking lever. It will thus be seen that the movement of the core 3 in response to its attraction, on account of the magnetic influence of the winding 1, causes a rocking of the rocking bar 8 and this rocking effect serves to establish electrical contact relations between a contact terminal 13 provided upon the left hand extremity of the lever 8 and two stationary contact posts 14 and 15. The contact element 13 is held in the lever by means of the screw 16 as shown. The contact elements 14 and 15 are held in the binding posts 17 and 18 respectively and are adjustable as shown toward and away from the movable contact element 13. Now, when

the lever 8 is rocked from its normal position as shown in the illustration of Fig. 1, it may cause engagement between the contact element 13 and either of the contact elements 14 or 15 depending upon whether the voltage in the circuit with which the winding 1 is connected is raised or lowered. It will of course be apparent that when the voltage of the supply circuit is of a value which is approximately a slight deviation from the voltage, which would either make or break contact between the element 13 and the elements 14 and 15 respectively, that the movable element remains close to either one or the other of these elements and slight changes of voltage up or down will cause vibration of the lever 8 with periodically touching of one or the other of the contacts 14 or 15, thereby producing an arc and consequent welding together of the contacts. This is a serious defect to the elimination of which my invention is directed.

In accordance with my invention I provide two coils 19 and 20 which act upon a common core 21, which common core is of course shorter than the distance between the top of the coil 19 and the bottom of the coil 20 so that an energization of either coil will draw the core 21 up or down under the controlling influence of an adjustable spring 22. The core 21 at its lower extremity as stated is secured to a spring 22 and at its upper extremity carries a rod 23 which is pivotally secured to the left hand extremity of the lever 8. It may be stated right here that the contact elements 14 and 15 are mounted on flexible springs 24 and 25 respectively, and the rocking lever 8 has a spindle 9 through the agency of which it is rotatably mounted.

In the operation of contact making voltmeters, the arrangement is such that should the elements 13 and 14 make contact, for instance, a suitable motor or other device is set in operation to raise the voltage and should elements 13 and 15 make contact the same devices are set in operation to lower the voltage. Now when the elements 13 and 14 are in vibratory contact, it will be apparent that the motor devices are subject to frequent and severe shocks due to sudden starting and stopping which not only tends to burn them out and render the circuit which they are to control unstable in voltage, but also tends to burn these contacts 13, 14 or 15 together, thus rendering the entire device ineffective.

The circuit arrangement of my corrective device is such that the circuit through the coil 19 is serially arranged with contact elements 13 and 14 and the circuit through the coil 20 is serially arranged with respect to contact elements 13 and 15. Thus should elements 13 and 14 be in vibratory contact, sufficient current flows through the coil 19

to attract the core 21 upwardly and to close the contacts 13 and 14. The same is true as respecting coil 20 and contact elements 13 and 15. It will be seen therefore that when the elements 13 and 14 are in vibratory contact, or have broken their contacts so that an arc may be established between them which permits some current to flow, that the coils 19 or 20 become operative to permanently close the contact and the motor devices may work to affect their change in voltage. This change in voltage goes on until the current in the winding 1 is of proper size to operate the core 3 so as to overpower the effect of the auxiliary influence of the coils 19 or 20 and thereby disrupting the contact between the elements 13 and 14. It might be stated that in the preferred form of adjusting this instrument, the arm 8 may be designed to be normally horizontal, and it will keep a horizontal position if the voltage is normal. Now the auxiliary devices maintain the contacts in closed relation until the voltage of the supply circuit gets back to normal and then a positive break is made and the arm 8 assumes its preferably horizontal position. It will of course be understood that for the current conditions in the winding 1 to be of such character as to overpower the auxiliary influence of the coils 19 and 20, said current is such that after the contact is broken the core 3 is in such a position that the contact element 13 will be removed a considerable distance away from the elements 14 or 15 with which it was last in contact, for the reason that the current in the winding 1 must have changed sufficiently not only to have separated these contacts without the influence of the coils 19 or 20, but in addition must have changed sufficiently to overpower the action of these auxiliary coils, consequently substantially separating these contact making elements. Switch levers 26 and 27 in conjunction with contacts 28 and 29 can be used for compensating purposes.

Circuit arrangements of the devices described will be apparent from Fig. 3, where I show the winding 1 as having a series coil 30 and a bridged coil 31, the series coil receiving its current from a series transformer 32 inserted in the line wire 33 of the circuit 33, 34. The circuit 33, 34 is one phase of a three phase system supplied by the three phase generator diagrammatically indicated at 35. The pressure coil 31 receives its current from the pressure transformer 36. Resistances 37 and 38 are respectively in series with the coils 19 and 20. It will of course be understood that the energization of coil 19 draws the core 21 upwardly and an energization of the coil 20 draws the core 21 downwardly.

The system under consideration has a pres-

sure regulating winding 39 in inductive relation with a coil 40 serially in the line circuit and this coil 40 in its operation serves to transform some of the current in such a way 5 as to boost the pressure through the agency of the coil 39. This boosting effect as to which of course I claim nothing being well understood in the art is accomplished preferably by rotating change of inductive relation between the coils 40 and 39, and this is accomplished by the motor regulating devices referred to in the specification, which in this instance may be a three phase motor, herein illustrated by a three phase armature 10 winding 41, it being understood that the amount of inductive relation between the coils 39 and 40 depends upon the position of the movable element of the motor 41.

At the central station where the devices 20 above described are used there is usually provided an auxiliary source of three phase current 42, 43 and 44 which is used to operate these devices. The motor 41 is operated from this source and one of its terminals is 25 permanently connected to the three phase conductor 42 by means of the conductor 45. The other terminals of the motor connect to contact terminals 46 and 47 to which current is supplied by the switch elements 48, 30 49, 50 and 51. The elements 48, 49, 50 and 51 are what are technically termed limit switches controlled by the rotating element of the motor to prevent burning out of the motor when it has moved to its limit in one 35 direction. The current to the motor is reversed and its operation controlled by the relays 52 and 53 which are serially included with the contact elements 13 and 15 respectively and through the agency of the rocking lever 8 between the three phase terminals 40 44 and 43.

When the elements 13 and 14 are in contact, relay 52 operates through the agency of its associated contact elements to rotate the 45 motor devices 41 in one direction, and when relay 53 operates the connection is reversed and the motor rotates in the contrary direction.

It will be seen from the illustration that 50 the coils 19 and 20 of my improved corrective device are serially associated in circuit with the elements 13 and 14 and 15 respectively and resistances 37 and 38 respectively between the terminal 44 through the agency 55 of the conductor 54 and terminal 43 through the agency of the conductor 55 so that these coils also receive their current from this three phase source. It will be apparent of course that the relays 52 and 53 serve merely 60 as reversing switch operating devices. It will be apparent that the coils 19 and 20 serve to either positively keep the elements 13 and 14 in positive engagement or else to insure their separation a sufficient distance 65 to prevent arcing or vibration, or fluttering

contact. As before stated, I do not mean to imply by the above detailed description that my invention is limited in its correcting effects to use in a system such as described, but in order to thoroughly describe its operation and its effect, I have included in this 70 description an operative system.

Having however thus described one form which my invention may take and one form of its many applications, what I claim as 75 new and desire to secure by Letters Patent is:

1. In combination, a pair of stationary contact members, a floating contact movable from a position in which it engages one of 80 said members to a position in which it engages the other of said members, a pivotally mounted bar on which said contact is fixedly mounted, and electromagnetic means 85 energized and controlled solely by the engagement of the contact with either member for prolonging the period of such engagement.

2. In combination, a pair of stationary contact members, a floating contact movable 90 from a position in which it engages one of said members to a position in which it engages the other of said members, a pivotally mounted bar on which said contact is fixedly mounted, electromagnetic means for 95 operating said contact, and electromagnetic means energized and controlled solely by the engagement of the contact with either member for prolonging the period of such engagement.

3. In combination a circuit closing element, a contact element with which it is adapted for electrical association, electromagnetic means adapted to operate said element to close or open said contact, said electromagnetic means being susceptible of varying energizations, and auxiliary means controlled solely by the engagement of said elements for governing said element to partly neutralize the effect of the first aforesaid electromagnetic means during the portion of a cycle of the operation of said element thereby to insure positive contact or positive open circuit between said element and its associated contact.

4. In combination an electric circuit having power fluctuations, a circuit controlling element, electromagnetic means responsive to fluctuations in said electric circuit to operate said element, a stationary contact with 115 which said element is adapted for electrical association, and means controlled solely by the engagement of said elements for acting upon said element to render it unresponsive to the influence of said electromagnetic means during that portion of the cycle of its 120 operation between positive closure of the contact through said element and a position of said element removed a predetermined 125 distance from said contact.

5. In combination a circuit closing element comprising a swinging bar and a contact fixedly mounted thereon, electromagnetic means operating upon said element tending to gradually change its position in accordance with changes of energization of said electromagnetic means, a contact with which said element is adapted for periodic engagement to change circuit conditions, and additional electromagnetic means governing the operation of said element and under the control solely of said element.

10. In combination a circuit closing element comprising a swinging bar and a contact fixedly mounted thereon, electromagnetic means operating upon said element tending to gradually change its position in accordance with changes of energization of said electromagnetic means, a stationary contact with which said element is adapted for periodic engagement to change circuit conditions, and additional electromagnetic means governing the operation of said element, and receiving current serially through

15. In combination a circuit closing element comprising a swinging bar and a contact fixedly mounted thereon, electromagnetic means operating upon said element tending to gradually change its position in accordance with changes of energization of said electromagnetic means, a contact with which said element is adapted for periodic engagement to change circuit conditions, and additional electromagnetic means governing the operation of said element and under the control solely of said element.

20. In combination a circuit closing element comprising a swinging bar and a contact fixedly mounted thereon, electromagnetic means operating upon said element tending to gradually change its position in accordance with changes of energization of said electromagnetic means, a stationary contact with which said element is adapted for periodic engagement to change circuit conditions, and additional electromagnetic means governing the operation of said element, and receiving current serially through

25. In combination a circuit closing element and its associated contact, whose circuit is controlled solely thereby.

30. A device of the character described comprising a circuit closing element, electromagnetic means to whose influence said element is gradually responsive, a stationary circuit terminal adapted for electrical association with said element, and means controlled solely by the engagement of said elements to influence the operation of said element whereby under the gradual change of influence of said electromagnetic means said element is adapted for positive association with the terminal or is adapted to be removed therefrom a sufficient distance to prevent injurious influence.

35. In witness whereof, I hereunto subscribe my name this 30th day of September A. D., 1910.

40. CHARLES J. HEJDA.
